UNITED STATES PATENT OFFICE.

GEORGE D. BALDER, OF FOLEY, MINNESOTA.

STANCHION.

1,198,989.

Specification of Letters Patent. Patented Sept. 19, 1916.

Application filed August 31, 1915. Serial No. 48,314.

To all whom it may concern:

Be it known that I, GEORGE D. BALDER, a citizen of the United States, residing at Foley, in the county of Benton and State 5 of Minnesota, have invented certain new and useful Improvements in Stanchions; and I do hereby declare the following to be a full, clear, and exact description of the invention, such as will enable others skilled in the art 10 to which it appertains to make and use the same.

The primary object of this invention is to provide a cheap, durable, and efficient stanchion that will be automatically operated 15 upon the insertion of the head of the animal into the frame of the structure.

Another object of the invention is to provide a stanchion of the nature above set forth, the clamping portions of which when 20 moved to set or unlocking position, will be so held in the said position that they will be only operated upon the insertion of the head of the animal within the frame.

A further object of the invention is to 25 admit of the releasing of the clamping portions of the stanchion from said position, being only effected by the animal when the animal's head is positioned within the frame.

Other objects will appear and be better 30 understood from that embodiment of my invention of which the following is a specification, reference being had to the accompanying drawings forming a part thereof, in which:—

35 Figure 1 is a front elevation of the stanchion showing the clamping members in clamping position. Fig. 2 is a side elevation of the view shown in Fig. 1. Fig. 3 is a front elevation of the stanchion showing 40 the clamping members in unclamping position. Fig. 4 is a sectional view through the upper ends of the clamping members of the stanchion, and Fig. 5 is a sectional detail view through the lower ends of the 45 clamping members.

Referring to the drawings more in detail, the letter A designates a stanchion as an entirety, which consists of a frame having the opposite side bars 1 and 2 and connecting 50 end bars 3 and 4. Positioned within the frame is a pair of vertically disposed companion clamping members 5 and 6. The lower ends of the members 5 and 6 are curved in the direction of each other, as 55 shown by the numerals 7 and 8 respectively.

The opposite sides of the curved end 7 of the clamping member 5 have secured thereto

a pair of substantially V-shaped plates 9. These plates 9 have one end secured to the adjacent side of the curved end 7, by means 60 of pins 10. The opposite ends of the plates 9 extend beyond the terminal of the curved end 7 and are positioned, respectively on opposite sides of the curved end 8 of the clamping member 6 and pivoted thereto by 65 means of the pivot pin 11.

A contractile spring 12 is disposed below the curved ends of the clamping members 5 and 6 and spaced therefrom and the opposite ends of the wire which form the spring 70 are bent inwardly from the extreme coils of the spring as shown at 13 and 14 and partially overlie the upper surface of the spring, the said ends of the wire are then continued from the inwardly bent portions 75 13 and 14 and curved outwardly as at 15 and 16 to engage around the under surface of the curved ends 7 and 8, and secured thereto by means of fastening means 17. The ends of the wire are then bent upwardly from 80 the curved portions 15 and 16, and parallel with the clamping members 5 and 6 and are secured thereto by means of fastening elements 18.

The upper end of the clamping member 7 85 is provided with an angularly and inwardly extending arm 19. This arm 19 is provided with a longitudinal slot 20, which opens into one end and the upper and lower sides of the arm. A latch 21 is associated with 90 the arm 19 and is formed of a single piece of wire, which is bent approximately centrally, upon itself and formed to provide a downwardly curved manipulating portion 22, one end of the wire being extended 95 downwardly and into the slot 20 and medially coiled to provide an eye 23, which receives a pivot pin 24 which is positioned within the slot and which has its opposite ends positioned in opposite walls of the slot 100 20 and the terminal of the adjacent end of the wire extends below the arm 19 to provide a trigger 25, for a purpose to be hereinafter stated, and has an eye formed thereon as shown at 26. The opposite end of the 105 wire is bent and extended outwardly from the manipulating portion 22, and overlies the free end of the arm and has its terminal extended downwardly and formed substantially into a compound curve as shown at 110 27, to provide a locking portion, for a purpose to be hereinafter stated.

The clamping member 6 is provided with a right angularly and inwardly extending

arm 28. This arm 28 is disposed below the upper terminal of the clamping member 6 and in line with the trigger 25 and it is adapted to engage the trigger when the 5 clamping members are moved toward each other.

The clamping member 5 has pivoted thereto, one end of a trip lever 29. The opposite end of the trip lever is received 10 by a keeper 30, which is secured to the clamping member 6. The terminal of the free end of the trip lever is bent into substantially U-shape as shown at 31, and one side of the U-shaped terminal is curved outwardly, at a point below the point of junction with the bight portion of the U-shaped member as is shown at 32.

When the clamping members 5 and 6 are in unclamping position, as shown in Fig. 3, 20 the U-shaped terminal of the trip lever engages over the lower horizontal arm 33 of the keeper and holds the clamping members set or in unclamping position. The trip lever is so disposed on the clamping members, that it will readily admit of the animal inserting its head thereunder and when the upper surface of the animal's neck comes in contact with the trip lever, the latter will be raised upwardly, resulting in the disengaging of the U-shaped portion 31 of the trip lever, from the arm 33 of the keeper, and the moving of the clamping members toward each other or to clamping position, by means of the spring 12, which is adapted 35 to be placed under tension when the clamping members are moved to open position. When the clamping members are moved into operative position the arm 28 engages the trigger 25, to cause the compound 40 curved portion 27 to engage over the upper end of the clamping member 6 and hold the clamping members in closed position, as shown in Fig. 1. The arm 19 has mounted thereon a U-shaped member 34, which is 45 formed of spring metal and has the terminals of its sides projecting beyond the free end of the arm 19 and deflected outwardly as shown at 35 and 36. The deflected terminals 35 and 36 are adapted to receive 50 therebetween the upper end of the clamping member 6, when the latter is moved to closed position, as shown in Fig. 1, and to frictionally engage the same so as to assist the arm in holding the latter in closed position.

The clamping member 6 has associated therewith a yoke-shaped member 37. This member is formed preferably of a single piece of wire bent and engaged over the 60 clamping member as shown in Fig. 8 and coiled to provide eyes 39 and 40 which receive the opposite terminals of pin 41, which extends through the clamping member 6,

the ends of the wire being extended outwardly in parallelism as at 42 and 43 and 65 adapted when the clamping members are in open position to engage, respectively, the opposite sides of the cross bar 2 of the frame and hold the clamping members against lateral movement, as shown in Fig. 1. When 70 the clamping members are in their closed position the trip lever 29 can be swung upwardly, as shown in dotted lines in Fig. 1, so as to admit of the curved portion 32 engaging over the upper horizontal arm 44 75 of the keeper and hold the trip lever from engagement with the neck of the animal.

The clamping members 5 and 6 are suspended within the frame by means of chains 80 45 and 46. These chains are positioned, respectively, at the upper and lower ends of the frame, and are secured thereto in any suitable manner and the chain 45 has one end connected to the arm 19 and the chain 46 has one end connected to the spring 12, 85 in any suitable manner. The chains 45 and 46 admit of the clamping members being moved in unison with the movement of the head of the animal, when the animal positions its head between the clamping members, thereby permitting of free movement 90 of the head of the animal between the clamping members.

From the foregoing description taken in connection with the accompanying drawings, it will be seen that I have provided a durable and efficient stanchion that can be manufactured cheaply and be automatically operated upon the insertion of an animal's head between the clamping members of the 100 stanchion.

Having thus described my invention, what I claim as new is:

In a stanchion, the combination with the clamping section, of a trip lever having one 105 end pivotally connected to one of the clamping sections, and having its opposite end provided with a U-shaped portion, one side of the U-shaped portion having an offset portion, means on the other clamping section for detachably engaging the U-shaped portion of the trip lever when the clamping sections are in unclamping position, and a second means on the last mentioned clamping section for engaging in the offset portion of the said side of the U-shaped portion when the clamping sections are in 110 clamping position, as and for the purpose specified.

In testimony whereof I affix my signature in presence of two witnesses.

GEORGE D. BALDER.
